(57) **CLAIM**

The ornamental design for a cosmetic applicator as shown and described.

DESCRIPTION

FIG. 1 is a perspective view of a cosmetic applicator, showing the new design in a first embodiment;

FIG. 2 is a front view of the cosmetic applicator of FIG. 1; FIG. 3 is a back view of the cosmetic applicator of FIG. 1; FIG. 4 is a left side view of the cosmetic applicator of FIG. 1;

FIG. 5 is a right side view of the cosmetic applicator of FIG. 1;

FIG. 6 is a top view of the cosmetic applicator of FIG. 1; FIG. 7 is a bottom view of the cosmetic applicator of FIG. 1;

FIG. 8 is a perspective view of the cosmetic applicator shown in a second embodiment with a flocked surface;

FIG. 9 is a front view of the cosmetic applicator of FIG. 8; FIG. 10 is a back view of the cosmetic applicator of FIG. 8; FIG. 11 is a left side view of the cosmetic applicator of FIG. 8;

FIG. 12 is a right side view of the cosmetic applicator of FIG. 8;

FIG. 13 is a top view of the cosmetic applicator of FIG. 8; and,

FIG. 14 is an enlarged bottom view of the cosmetic applicator of FIG. 8.

The broken lines shown in the drawings depict portions of the cosmetic applicator that form no part of the claimed design.
